REINFORCED HEMSTITCHING

Hearne Swink, Salisbury, N. C., and Paul White Douglass, Ridgewood, N. J., assignors to Cannon Mills Company, Kannapolis, N. C., a corporation of North Carolina

Application July 25, 1935, Serial No. 33,132

7 Claims. (Cl. 112—266)

Our invention relates to a new form of reenforced hemstitching, as well as to the method of producing the same.

Hemstitching of sheets, pillow cases, and the like has long been resorted to, in order to impart a pleasing appearance to the finished articles. However, the disadvantage has always been recognized that hemstitching as hitherto practiced has been quite delicate and fragile as compared to the fabric itself of the article, so that often after but a comparatively few washings the article will begin to tear or rip along the line of hemstitching.

Thus because of their lack of durability, hemstitched articles have come into nowhere near the widespread use to which they are entitled by virtue of their superior appearance. Only the relatively wealthy could afford their use in quantity.

It has been recognized that if only it were possible to retain the pleasing appearance of hemstitching, while increasing the durability of the hemstitched article, the useful range of hemstitching would increase materially.

We have devised a new method of reenforcing hemstitching, giving rise to a product which while on its face side it has the appearance of ordinary hemstitching, at the same time it is provided in the rear of the hemstitching with a reenforcing backing and an extra row of hemming.

In brief, to produce our reenforced article, a sufficient number of threads of the filling are drawn to leave the space desired, this operation being performed on the usual machine. The hemstitching is then carried out, preferably on a machine, and whereas in the ordinary hemstitching the end of the hem or raw edge is turned in, is sewed, and both edges are bound to form the spoke of the hemstitching, all in one operation, in our case the end of the hem or raw edge is turned out, away from the region of hemstitching, leaving a free portion sufficient to overlap the spokes of the hemstitching. Thereafter, in a separate or second operation, this free end is folded in, or under, and is hemmed, thus providing a backing and a reenforcing hem for the row of hemstitching.

An object of our invention, then, is to produce a new form of hemstitching.

Another object is to produce a new method of hemstitching.

Other objects and advantages will more fully appear in connection with the following description.

55 One at-present-preferred form of our invention

is shown by way of example in the accompanying drawing wherein:

Fig. 1 is a front elevation of a sheet or the like hemstitched according to our new process;

Figs. 2 and 3 are fragmentary transverse sections on a scale approximately twice that of Fig. 1, showing two separate steps in the process of hemstitching, while

Fig. 4 is an end elevation of the sheet, on the same scale as Fig. 1.

In carrying out the process, a number of the threads of the filling of a sheet 1 or the like are pulled out in the region 2 in any suitable manner, as by one of the several known machines adapted for this purpose.

A hem is next formed by folding over the end of the sheet to form the two legs 3 and 4, and then the raw edge 5 is folded outwardly. The hem thus will be seen to have an inner end, adjacent the body material, as well as an outermost, free end.

Ordinarily, as has been suggested in the first part of this description, the raw edge is turned under, or inwardly, the hem being sewn, and both edges along the region of pulling being bound to form the spokes of the hemstitching, all in a single operation.

However, in our case, the folded-back edge 5 is gathered at 6, and by means of the usual binding stitching 7, is secured to the hemstitching, the spokes of which are shown at 8.

The raw edge 5 is then folded down, as shown in Fig. 3, and the portion 9 thereof is folded in or under. The reenforcing or backing portion 10 of the raw edge 5 is designed to have sufficient length to overlap the spokes of the hemstitching.

The fold 11 of the raw edge 5, joining the portions 9 and 10, now lies snugly against the body portion 1 of the sheet, and is now secured thereto as by a row of conventional stitching 12.

It is obvious from the foregoing that the backing 10 fully reinforces the hemstitching 8, while leaving its surface appearance substantially unchanged. At the same time, instead of the fragile hemstitching being called upon to withstand all the tensional strain when the sheet is stressed, which causes the normal hemstitching to rupture quickly, the stress will be distributed between the stitching 7 and the stitching 12, and as a matter of fact, the greater part of the stress will be taken up by the stitching 12.

As a typical instance, a pillow case hemstitched according to our process was laundered 35 times without apparent weakening of the hemstitching.

It will be seen then, that our invention com-

prises producing a reenforced hemstitched article, having a strengthening backing and a double row of hemstitching, by drawing the required threads from the filling, folding over a hem, folding the 5 raw edge of the hem outwardly and backwardly, performing the hemstitching operation and then folding the raw edge downwardly and inwardly, to overlie the hemstitching, at which time the said raw edge is hemmed in place.

10 It will be readily understood that once the broad aspects of our invention are disclosed, many modifications and adaptations will readily occur to those skilled in the art, but all falling within the scope of our invention. Accordingly we in- 15 tend that such invention is to be limited only by the scope of the appended claims.

We claim:

1. A new form of hemstitching, comprising a material having hemstitching therein, and a backing 20 formed on said material in the rear of and extending across said hemstitching and constituting an integral part of said material.
2. A new form of hemstitching, comprising a material having hemstitching therein, a backing 25 on said material in the rear of and extending across said hemstitching, the said backing having a free end thereon, and a second row of stitching securing the free end of said backing to said material.
- 30 3. A new form of hemstitching, comprising a material having hemstitching in one surface thereof, a hem in said material and forming part thereof and disposed on one side of said hemstitching and stitched thereto, and a free edge on said hem overlapping the rear of said hemstitching and reenforcing the same and having an end thereon, and a row of stitching securing the end of said free edge to the material.
4. A new form of hemstitching, comprising a 40 material having hemstitching in one surface thereof, a hem in said material and forming part thereof and disposed on one side of said hemstitching and stitched thereto, and a free edge on said hem overlapping the rear of said hem- 45 stitching and reenforcing the same and having

an end thereon, and a row of stitching securing the end of said free edge to the material, a gather being formed between the free edge and the body of the hem, and the said gather being stitched to the hemstitching along with the hem.

5 5. A method of producing reenforced hem- 10 stitching, comprising folding one end of the material onto the body thereof to form a hem, turning the raw edge of the end of the material outwardly and away from the body material, hem- 15 stitching the body material at the inner end of the hem and uniting the end of the hem to the body material, turning the raw edge of the end of the material inwardly in overlapping relation to the hemstitching, and securing the end thus turned to the body material.

6. A method of producing reenforced hem- 20 stitching comprising folding one end of the material onto the body thereof to form a hem, turning a width of the raw edge of the end of the material outwardly and away from the body material sufficient to overlap the hemstitching, hem- 25 stitching the body material at the inner end of the hem and uniting the end of the hem to the body material, turning the raw edge of the end of the material inwardly in overlapping relation to the hemstitching, and securing the end thus turned to the body material.

7. A method of producing reenforced hem- 30 stitching, comprising folding one end of the material into the body thereof to form a hem, turning the raw edge of the end of the material outwardly and away from the body material, gathering the folded edge formed by the said turning between the hem and the raw edge portion, hem- 35 stitching the body material at the inner end of the hem while simultaneously by the same stitching securing the said folded edge to one side of the hemstitching, closely adjacent thereto, turning the raw edge of the end of the material inwardly in overlapping relation to the hemstitching, and securing the end thus turned to the body material.
